(57) **CLAIM**

The ornamental design for a ridged variable welt ball, as shown and described.

DESCRIPTION

FIG. 1 is a perspective view of the ridged variable welt ball of the present invention;

FIG. 2 is a top plan view of the ridged variable welt ball of FIG. 1;

FIG. 3 is a side view of the ridged variable welt ball of FIG. 2, the opposite side of the ball being a mirror image thereof;

FIG. 4 is a front view of the ridged variable welt ball of FIG. 2; and,

FIG. 5 is a rear view of the ridged variable welt ball of FIG. 2.
